CLAIM

The ornamental design for a gusset grip container, as shown and described.

DESCRIPTION

FIG. 1 is a top perspective view of a gusset grip container showing our new design;

FIG. 2 is a front view thereof;

FIG. 3 is a rear view thereof;

FIG. 4 is a first side view thereof;

FIG. 5 is a second side view thereof;

FIG. 6 is a top view thereof; and,

FIG. 7 is a bottom view thereof.

The broken lines represent portions of the gusset grip container, are for illustrative purposes only, and form no part of the claimed design.
